DESIGN FOR A SHOE HEEL

Myer S. Klein, Malden, Mass., assignor to Panther-Panco Rubber Co. Inc., Chelsea, Mass., a corporation of Massachusetts

Application August 22, 1933. Serial No. 49,078

Term of patent 7 years

To all whom it may concern:

Be it known that I, MYER S. KLEIN, a citizen of the United States, residing at Malden, in the county of Middlesex and Commonwealth of Massachusetts, have invented a new, original, and ornamental Design for a Shoe Heel, of which the following is a specification, reference being had to the accompanying drawing forming a part thereof.

In the drawing, Fig. 1 is a plan view of a shoe heel showing my new design; and Fig. 2 is a cross-section on the line 2—2 of Fig. 1.

I claim:

The ornamental design for a shoe heel as shown.

MYER S. KLEIN.
